UNITED STATES PATENT OFFICE.

SANFORD B. GLEASON, OF BALTIMORE, MARYLAND.

WIRE MATTRESS.

SPECIFICATION forming part of Letters Patent No. 274,312, dated March 20, 1883.

Application filed February 8, 1883. (No model.)

To all whom it may concern:

Be it known that I, SANFORD B. GLEASON, of the city and county of Baltimore, in the State of Maryland, have invented a certain 5 new and useful Improvement in Wire Mattresses, of which the following is a specification.

My invention relates to what is commonly known as a "woven-wire mattress"—that is 10 to say, a mattress consisting of a bed-bottom composed of interlocked springs or woven wire combined with end and side supporting-rails. It is my object to obtain what may be termed a "knockdown mattress" of this sort.

15 In order to explain my improvement, it will be necessary to set forth the manner in which woven-wire mattresses have previously been made and put together.

So far as I am aware, the stretching and 20 putting under tension of the wire bed-bottom have heretofore been done at the factory where the mattress is made. The ends of the wire bed-bottom are first attached to the end rails. One of the latter is attached to the side rails in 25 its proper place, and then these parts are put upon and attached to a stretching table or frame and the spring-wire bed-bottom by powerful appliances is stretched. While the bed-bottom is maintained in this state of tension 30 the side rails are applied and fastened to the other end rail, thus completing the mattress and holding the stretched bed-bottom in place. With the side rails and one of the end rails are usually combined adjusting devices, which 35 are employed to keep the bed-bottom, when it is in use, under proper tension; but these devices are arranged and adapted merely to keep the bed-bottom to the required pitch of tension, and are not adapted, and in fact cannot 40 be operated, to release and take off the tension below a certain narrow limit, if any. The consequence is that it is impracticable to take the mattress to pieces. The bed-bottom, even when slackened to the utmost limit of the adjusting device, (whose range of movement is 45 but two or three inches at the very most, while the bed-bottom is stretched about eight inches beyond its normal length,) still is under considerable tension, so that when the side 50 rails are loosened from either end rail the spring force of the released bed-bottom will separate the parts violently, throwing them

quite a distance and making the operation one of considerable danger, while after they are once separated they cannot be put together again without making use of special stretching appliances, such as were used at the factory in the first instance. Thus the mattress, both in transportation in the furniture dealer's establishment and in the house where it is to 60 be used, must be handled as a whole. In this shape it is bulky, inconvenient, and expensive as freight, and is also very liable to be injured; and it is also inconvenient and difficult to handle under any circumstances. It is 65 therefore obviously an advantage to so construct and arrange the parts that they may be detached and packed in small compass and need not again be assembled and put together until they are brought to the bedstead with 70 which the mattress is to be used.

The object of my invention is to obtain this result. To this end I combine with the end and side rails and elastic extensible wire bed-bottom stretching devices whose range of 75 movement is equal to the difference in length of the bed-bottom when entirely off tension and when stretched to the proper degree plus whatever further may be required in order to take up the slight slack which occurs after the 80 mattress has been in use. A wire mattress, when stretched for the first time in the factory, usually elongates about ten inches. When relieved from this tension it contracts about eight inches. The first stretching thus 85 permanently elongates it about two inches, so that subsequently to be put under proper tension it must be stretched eight inches. The range of movement of the stretching devices under these circumstances should be eight 90 inches at least, a sufficiently greater range being provided for in order to take up the very slight slack which may occur from time to time during the use of the mattress. Furthermore, the parts are so proportioned and 95 the stretching devices are so situated that the movable end rail to be operated on can be introduced into or engaged with them, with the bed-bottom attached to said end rail off tension.

100 The nature of my improvement and the manner in which the same is or may be carried into effect will be understood by reference to the accompanying drawings, in which—

Figure 1 is a perspective view of a wire mattress embodying my invention. Fig. 2 is a longitudinal vertical section of the same. Fig. 3 is a detached view of one of the stretching-
5 irons, which I prefer, on the whole, to employ, although it is manifest that the constructions may be varied without departure from my invention.

A A are the side rails. B C are the end rails, and D is the woven-wire bed-bottom. The bed-bottom is attached to the end rails in the usual way, and one of the end rails, B, is attached in stationary position to the side rails by bolts *a* passing down through the end rail
10 and the side rails, and having screwed onto their projecting lower ends nuts *b*. The rail B is thus held firmly and tightly in position by a connection which permits it to be readily applied to and removed from the end rails. The
15 other rail, C, is the movable rail. Its ends rest upon the side rails and upon the tops of bracket-like stretching-irons E, fastened securely one to the inner face of each side rail, with their upper faces about flush with the top of the side rails. In the upper face of each stretching-
20 iron is a longitudinal slot, *c*, which should be of sufficient length to permit the range of movement hereinbefore indicated. On the front end of each iron is a laterally-projecting boss, *d*,
25 forming a bearing for the pressure-screw, *e*, which screws through it, and is arranged so that when screwed forward it will bear against and push back the end of the end rail C opposite to it. On the under side of this boss is
30 a dowel, *f*, which enters a hole bored for it in the top of the side rail for the purpose of imparting greater strength to the parts at this point. The end rail C is held to the irons by headed bolts *g*, which pass down through it
35 and the slots *c*, and have screwed upon their lower ends nuts *h*. The parts are so proportioned and the stretching-irons are so situated that after the end rail B is attached and in

place end rail C can be secured in place on the stretching-irons in front of the points of the 45 retracted screws *e*, while the bed-bottom is entirely off tension. Then by advancing the screws the end rail C will be pushed back and the bed-bottom put under any required degree of tension. After retracting the screws, so as 50 to gradually take the tension entirely from the bed-bottom, the mattress can be taken apart without difficulty by removing the nuts *b* and *h*. It will thus be seen that the bed-bottom and end rails to which it is secured can be 55 folded together and packed separately from the side rails, thus not only economizing space in transportation and in the warehouse, but rendering it very much more easy to handle the mattress; nor need the mattress be put together until it is brought to the bedstead for which it is designed, thus making it much more convenient to carry into a private house.

What I claim as new and of my invention is—

A knockdown wire mattress consisting of an elastic and extensible wire bed-bottom, side rails, and stationary and movable end rails detachably connected therewith, in combination with stretching-devices carried by the side 70 rails, and positioned and having a range of movement substantially as described, so that the movable end rail operated on by them can be engaged with them without putting the bed-bottom under tension, and can then be moved 75 by them from this position to one in which the bed-bottom will be brought and maintained at full tension, as and for the purposes hereinbefore set forth.

In testimony whereof I have hereunto set 80 my hand this 8th day of February, 1883.

SANFORD B. GLEASON.
